WORK HOLDING ATTACHMENT FOR VISES

Edward Kochorosky, Two Rivers, Wis.

Application October 28, 1941, Serial No. 416,880

3 Claims. (Cl. 81—38)

This invention relates to vises and more particularly to a work-hold-down attachment therefor.

An object of this invention is to provide as a new article of manufacture a hold-down attachment for mounting on a movable jaw of a vise for holding the work down on a flat surface, such as the top of a bench or the like.

Another object of this invention is to provide an attachment of this kind which is simple in construction and may be applied to a vise without changing any of the present parts of the vise.

A further object of this invention is to provide an attachment of this kind which is formed with means for holding the device against movement relative to the vise and also against movement relative to the work.

With the foregoing objects and to others which may hereinafter appear, the invention consists of the novel construction, combination and arrangement of parts as will be more specifically referred to and illustrated in the accompanying drawing, wherein an embodiment of the invention is shown, but it is to be understood that changes, variations and modifications may be resorted to which fall within the scope of the invention as claimed.

In the drawing:

Figure 1 is a detail front elevation of a work hold-down attachment for a vise constructed according to an embodiment of this invention.

Figure 2 is a detail top plan of the device, and

Figure 3 is a detail end elevation of the device in applied position with respect to a vise jaw and an article of work.

Referring to the drawing, the numeral 10 designates generally a movable jaw of a vise which may be associated with a bench or table 11 having a flat upper surface 12. The vise jaw 10 as shown in Figure 3 is adapted to project slightly above the top surface 12 of the bench or table 11, and the forward face 13 of the jaw 10 is disposed at right angles to the upper or horizontal face 14 thereof.

In order to provide a means whereby an article of work 15 may be held down flat on the working surface 12 of the table 11, I have provided as a new article of manufacture, a work-hold-down attachment generally designated as 16. The attachment 16 comprises an elongated flat body 17 which is substantially rectangular in plan and also rectangular in end elevation. The lower face 18 of the body 17 is adapted to engage on the upper surface 14 of the jaw 10. A work holding jaw 19 is formed integral with the body 17

and projects forwardly and downwardly therefrom. The jaw 19 may be of a width substantially equal to the width of the body 17, and in end elevation the jaw 19 is formed with a downwardly inclined upper face 20 and a downwardly inclined lower face 21. The two faces or surfaces 20 and 21 are disposed in forwardly convergent relation and terminate at their forward ends in a vertically disposed work engaging face 22.

The face 22 is serrated throughout the length and width thereof so that when the surface 22 contacts with the adjacent end of the work 15, the jaw 19 will not slip relative to the adjacent end of the work. The jaw 19 is formed with a downwardly offset portion 23 which extends downwardly from the lower surface 18 of the body 17 thereby providing a right angularly disposed shoulder 24 which is adapted to confront and engage the vertical face 13 of the jaw 10. The rear side of the jaw 19 along the offset portion 23 thereof is formed with a pair of parallel and vertically spaced apart grooves 25 which extend inwardly from the rear vertical face 24 of the offset portion 23, thereby forming a plurality of vertically spaced ribs which are adapted to engage the vertical face 13 of the jaw 10 in order to hold the jaw 19 against vertical movement relative to the jaw 10. When the attachment 16 is in applied position, the lower or forward end of the jaw 19 will be normally disposed in upwardly spaced relation to the working surface 12 of the table 11, as shown in Figure 3.

The attachment hereinbefore described may be removably mounted on the jaw 10, or if desired, may be bolted or otherwise fastened to the upper surface thereof with the offset portion 23 engaging the working side of the jaw 10. When the jaw 10 is moved inwardly towards the adjacent end of the work 15, the jaw 19 will be tightly clamped between the jaw 10 and the adjacent end of the work 15. Since the upper edge of the work engaging face 22 of jaw 19 lies in a lower horizontal plane than the lower edge of rear face 24, a tight clamping of the jaw 19 between the jaw 10 and the work 15 will effect a downward pressure on the work 15 so as to maintain the lower side of the work 15 flat upon the working surface 12 of the table or bench 11. It will be understood that the other or opposite end of the work 15 may be engaged with a conventional bench stop or other abutment which may be mounted on the bench or table 11 and project upwardly therefrom.

What I claim is:

1. A work hold-down attachment for a vise comprising an elongated body positionable over the upper end of a movable vise jaw, a downwardly inclined work engaging jaw integral with said body terminating in a work engaging face, the rear end of said work engaging jaw extending right angularly and downwardly from the lower surface of said body for engagement with the forward side of said movable jaw, the extended rear end of said work engaging jaw being formed with a plurality of parallel longitudinal grooves to thereby provide longitudinal ribs between the grooves for engagement with said movable jaw, said ribs holding said attachment against upward movement relative to said movable jaw, and serrations carried by the forward edge of said work engaging jaw, the upper edge of the work engaging face of the work engaging jaw being in a plane lower than the lower edge of the rear end of said work engaging jaw.

2. A work hold-down attachment for a vise comprising the elongated body positionable over the upper end of a movable vise jaw, a downwardly inclined work engaging jaw integral with said body terminating in a substantially vertical work engaging face, the rear end of said work engaging jaw extending right angularly and downwardly from the lower surface of said body and having a face for engagement with the forward side of said movable jaw, the extended rear

end of said work engaging jaw face being formed with a plurality of parallel longitudinal grooves to thereby provide longitudinal ribs between the grooves for engagement with said movable jaw, 5 said ribs holding said attachment against upward movement relative to said movable jaw, and serrations carried by the forward edge of said work engaging jaw, said work engaging jaw having forwardly convergent and downwardly inclined upper and lower faces, said work engaging face having its upper edge in a plane lower than the lower edge of the jaw engaging face.

3. A work hold-down attachment for a movable vise jaw comprising a downwardly and forwardly extending work engaging jaw, said latter jaw being of substantially truncated V-shape in transverse section and the forward edge of said latter jaw being substantially vertical, serrations carried by said forward edge for engagement with the work, the rear edge of said latter jaw being substantially vertical and formed with a plurality of longitudinal parallel grooves, and a supporting body integral with said latter jaw and disposed at an obtuse angle relative thereto, 15 said body being offset upwardly from the lower side of said latter jaw and adapted to engage on the upper side of said movable jaw, said forward edge of said latter jaw having its upper edge in a plane lower than the lower edge of said rear edge of said latter jaw.

EDWARD KOCHOROSKY.
